UNITED STATES PATENT OFFICE

159,576

DOCUMENT HOLDER

Benjamin Bamford, Detroit, Mich.

Application September 11, 1947, Serial No. 141,325

Term of patent 3½ years

(Cl. D74—2)

To all whom it may concern:

Be it known that I, Benjamin Bamford, a citizen of the United States, residing at Detroit, in the county of Wayne and State of Michigan, have invented a new, original, and ornamental Design for a Document Holder, of which the following is a specification, reference being had to the accompanying drawing, forming a part thereof, in which:

Fig. 1 is a front elevational view of a document holder, showing my new design; and

Fig. 2 is a side elevational view thereof.

I claim:

The ornamental design for a document holder, substantially as shown.

BENJAMIN BAMFORD.
